METHOD FOR INDENTING TUBES

Hollis P. Brown and Walter R. Rikli, Pontiac, Mich., assignors to American Forging and Socket Company, Pontiac, Mich., a corporation of Michigan

Application July 26, 1954, Serial No. 445,532

6 Claims. (Cl. 29—548)

The present invention relates to method for indenting tubes. The invention is particularly applicable to the production of tubular brake pull rods of the type disclosed in prior copending application of Charles S. McCarthy, Serial No. 349,865.

As more fully shown in the prior copending application, the brake pull rod is formed of tubular stock having bar receiving indentations formed in alignment along one side thereof. These indentations are designed to cooperate with spring pressed balls serving as latch members in conjunction with the indentations of the pull rod. In order to facilitate outward movement of the pull rod to brake applying position, the ball receiving indentations are elongated in a direction longitudinally of the tube and are relatively deeper at one end than at the other. The deeper end of the indentations include generally spherical surface portions engageable throughout a substantial area of a latching ball. The indentations are given a shape in transverse cross-section such that the ball may be cammed outwardly of the ball receiving indentations by rotation of the pull rod about its axis.

The present invention has, as its object, the provision of a novel method for forming the ball receiving indentations in the tubular brake pull rod.

It is an object of the present invention to provide a method of forming a brake pull rod having indentations extending in alignment along one side thereof which comprises supporting a tubular member and advancing an aligned series of indentation forming elements disposed in parallelism with the axis of the tubular member along a path having radial and axial components with respect to the axis of the tubular member, thereby forming axially elongated indentations having substantially greater depth at one end than at the other.

It is a further object of the present invention to provide a method of producing indented pull rods as described in the preceding paragraph which includes the step of locating the tubular member angularly with respect to the path of advance of the forming elements by inserting in a slot in one end of the tubular member a flat locating key.

It is a further object of the present invention to provide a novel method of forming an indented tubular member which comprises locating a tubular member on a support body, relatively moving a pair of opposed jaws into gripping contact with opposite sides of the tubular member, and thereafter moving a series of aligned forming elements disposed in parallelism with the axis of the tube into forming contact with a side of the tube, the path of advance of the forming elements being located in a plane radial of the tubular member and extending in such plane at an oblique angle to the axis of the tubular member.

Other objects and features of the invention will become apparent as the description proceeds, especially when taken in conjunction with the accompanying drawings, wherein:

Figure 1 is a plan view of the die with the punch head removed.

Figure 2 is a longitudinal section of the assembled die punch head.

5 Figure 3 is a transverse section of the assembled die and punch head taken in the plane of the line 3—3, Figure 1.

Figure 4 is a plan view of the punch head.

Figure 5 is an enlarged sectional view on the line 5—5,

10 Figure 1.

Figure 6 is a detailed elevational view of the work lifter.

Figure 7 is a side elevational view of a forming element.

15 Figure 8 is a front elevational view of the forming element seen in Figure 7.

Figure 9 is a somewhat diagrammatic sectional view through a modified form of die and forming element combination.

20 Figure 10 is a fragmentary elevational view of an indented tubular member as produced by the present invention.

Figure 11 is a fragmentary section on the line 11—11, Figure 10.

25 Referring first to Figures 10 and 11, the present invention relates to method and apparatus for producing indented tubes useful for example as brake pull rods. In Figures 10 and 11 a section of such indented tube is illustrated at 10 having ball receiving pockets 12 indented therein. These pockets are elongated longitudinally of the tube as illustrated in Figure 10, and as best illustrated in Figure 11 are of gradually increasing depth toward one end. These pockets 12 cooperate with latching balls indicated at 14, the balls being spring pressed into engagement with the tubes and held against longitudinal movement.

30 In the relationship illustrated in Figure 12, it will be apparent that the balls 14 are effective to retain the tubular member 10 against movement in a direction to the left. On the other hand, forces applied tending to move the tubular member 10 to the right will have the effect of camming the balls 14 upwardly. In the same manner, the pockets 12 have a radius of curvature at their point of greatest width somewhat greater than the radius of curvature of the balls 14 so that the balls may also be cammed outwardly from the indentation or recess by rotation of the tubular member.

35 Referring now to Figures 1—8, there is illustrated a preferred form of the apparatus for practicing the novel method of indenting the tubular members 10. As seen in these figures, the apparatus comprises a die 20 having upwardly extending posts 22 adapted to be received within bushings 24 carried by the punch or forming head 26 illustrated in Figure 4.

40 As best seen in Figures 3 and 5 the die 20 comprises a lower supporting plate 28 to which is fixedly mounted an elongated jaw member 30, this member being bolted or otherwise secured to the plate 28 as indicated at 32 and abutting against an elongated member 34 seated in a recess formed in the upper surface of the plate 28. Slidably mounted on a bearing plate 36 recessed in the upper surface of the plate 28 is a movable jaw 38, the movable jaw 38 having connected thereto threaded rods 40 each of which has a spring abutment washer 42 located adjacent its outer end and retained in position by a lock nut set illustrated at 44. Bolted or otherwise secured to the upper surface of the die plate 28 is an elongated block 46 having spring receiving recesses 48 therein which receive compression springs 50. The compression springs 50 bear against the spring abutment washer 42 and bias the movable jaw 38 to the right as seen in Figure 7. The block 46 bears against a locator strip 52 recessed in the upper surface of the die plate 28.

The stationary jaw 30 and the movable jaw 38 are provided with confronting recesses 54 in which are slidably mounted guide pins 56 urged outwardly of the recesses by compression springs 58. The pins 56 are provided with elongated slots 60 receiving the reduced ends of set screws 61 retaining the pins in the recesses and permitting limited longitudinal movement thereof.

Secured to the underside of the head plate 100 are cam blocks 62 having an inclined cam surface 63 adapted to cooperate with a correspondingly inclined camming surface 64 formed on the movable jaw 38. The rods 49 pass through elongated openings 65 in the cam blocks 62. The arrangement is such that upon downward movement of the head 26 cam surface 63 engages cam surface 64 and cams movable jaw 38 to the left as seen in Figure 3, thereby clamping the tubular member 10 firmly in position prior to engagement therewith of the forming elements 102.

The die plate 28 is provided adjacent one end with a block 68 which is bolted or otherwise secured thereto as indicated in Figure 5. The block 68 is located adjacent an elongated locator strip 70 mounted in an elongated recess formed in the upper surface of the locator plate 28. Outwardly of the block 68, as best illustrated in Figure 2, is a smaller block 72. The blocks 68 and 72 have aligned openings 74 and 76 therein through which extends a longitudinally slidable locator element 78. The openings 74 and 76 are transversely elongated as best illustrated in Figure 5, to permit transverse rocking movement of the locator element 78. The locator element 78 is provided with a plurality of pin receiving openings 80, a selected one of which receives a pivot pin 82, the lower end of the pin being received in a pin receiving opening 84 in the block 72. The inner end of the locator element 78 is tubular and receives a rod 86, the rod including a transverse pin 88 the ends of which extend into aligned elongated slots 90 formed in the tubular portion of the locator element 78. At its inner end the rod 86 is provided with a blade 92 and a spherically formed button portion 94. The tubular member 10 is provided with a slot at the left hand end as illustrated in Figure 2, and the blade 92 enters into the slot and the button 94 enters into the end of the tube, thus serving to locate the end of the tube. The rod 86 is urged outwardly of the tubular portion of the locator element by a compression spring 96 so that the device urges the tubular member to the right against an abutment surface located at the opposite side of the die. The purpose of the blade 92 is to insure proper angular relationship between the slot at the end of the tube and the aligned row of indentations formed therein by the apparatus.

Associated with the die 20 is the punch or forming head 26 which comprises a plate 100 mounted for vertical guided movement toward and away from the die 20 by the pins 22 and the bushings 24 previously described. An assembly of forming elements 102 are mounted in an elongated block 104 mounted for sliding movement at the underside of the head plate 100. In order to support the block or strip 104 for longitudinal sliding movement, ways are provided comprising strips 106 and 108 spaced apart by an elongated spacer strip 109, to which are bolted or otherwise secured elongated strips 110 and 112. Adjacent edge portions of the strips 110 and 112 underlie downwardly facing shoulders 114 at the sides of the elongated strip 104. The underside of the strip 104 is provided with an elongated recess 116 adapted to receive an assembly of forming elements 102, these elements being rigidly clamped in position therein by a wedge strip 118 which engages the sides of the forming elements 102. The assembly of forming elements 102 is further positioned by a wedge block 120 engaging the inclined surface at one end of the recess 116 which receives the forming elements 102. By this construction the forming elements are rigidly locked in position in the elongated

strip or block 104. The ways previously described allow longitudinal movement of the block or strip 104. As best seen in Figure 2, one end of the block 104 is provided with an inclined or beveled surface 122. The adjacent surface of the block 64, carried by the die plate 28, is correspondingly beveled and the two beveled surfaces operate as a cam to force the block or strip 104 to the right as seen in Figure 2 upon downward movement of the plate 100. In order to retain the longitudinally slideable block or strip 104 in proper position to be actuated by the cammed surfaces just referred to, a block 124 is rigidly secured to the underside of the head plate 100 and is provided with a pair of spring receiving recesses 126, as best illustrated in Figure 4, compression springs 128 being received in these recesses and bearing against the right hand end of the block or strip 104. Forming elements 102 are alternated with spacers 103, and the tube is slotted axially between successive operations.

From the foregoing construction it will be apparent that downward movement of the head plate 100 results in a shifting movement of the block or strip 104 together with the forming elements 102 to the right. As a result of this the forming elements 102 are given a movement relative to the tubular member 10 along a path having substantial radial and axial components with respect to the axis of the tube. In the illustrated embodiment of the invention the inclined surface 122 and the corresponding surface of the block 64 extend at an angle of 30 degrees to the axis of the tube and thereby the forming elements are moved into forming engagement with the tube along a path having equal radial and axial components.

The right hand end of the tubular member 10 engages a ground locating surface on an adjustable stop block 130 having locating surfaces 132, 134, 136, 138 and 140. The block 130 is adjustable transversely of the die plate 28, an elongated slot 142 and clamping bolt 144 being provided for this purpose. The block is accurately located in position against a locating strip 146 received in an elongated recess 148 machined in the upper surface of the plate 28.

In order to lift the completed tubular member 10 from the die following the indenting operation, there is provided a lifter blade 150 the inner end of which underlies the tubular member 10. The blade 150 is mounted in a block 152 bolted or otherwise secured to the upper surface of the plate 128 and is pivoted thereat by a pivot pin 154.

With the foregoing apparatus described, the operation will be apparent but will be briefly reviewed. With the head 26 elevated a tubular member is positioned between the jaws 30 and 38 which at this time will be slightly separated. The tubular member is retained in accurately located position between the jaws by engagement with the spring pressed plungers or pins 56, the inner ends of which are cylindrically recessed as best illustrated in Figure 3. At the same time the tubular member 10 is positioned with a slot at the left hand end thereof as viewed in Figure 2, the slot receiving a portion of the flat blade 92. The left hand end of the tubular member also receives the spherical locating button 94 and the rod 86, urged to the right by the spring 96, presses the right hand end of the tubular member 10 against the appropriate one of the locating surfaces 132, 134, 136, 138 or 140, according to adjustment of the locator block 130. Downward movement of the head initially closes the movable jaw 38 on the stationary jaw 30, this movement being accompanied by a transverse shifting of the tubular member 10 which during this movement is maintained between the jaws by simultaneous yielding of the locator pins 56. This transverse yielding movement of the tubular member 10 is accompanied by swinging movement of the locating assembly including the locator element 78 and rod 86 about the vertical axis of the pin 82. Downward movement of the head 26 causes longi-

tudinal sliding movement of the block or strip 104 as a result of the camming engagement of the surface 122 thereof and the corresponding beveled surface provided on the stationary block 64, this movement operating against compression springs 128. Accordingly, the forming elements 102 have the lower forming portions thereof forced into the upper surface of the tubular member 10 along oblique paths having radial and axial components with respect to the axis of the tube. As a result of this relative motion of the lower forming portions of the elements 102, they are progressively depressed downwardly and axially to produce elongated indentations in the upper surface of the tube extending longitudinally thereof, the portions of each indentation at the right hand end thereof as viewed in Figure 2, being deeper than portions thereof toward the left.

When the head is raised the indented tubular member 10 is freed from its support by depressing the outer end of the lifter 150 downwardly thus swinging the lifter about its pivot axis 154 and raising its inner end to elevate the indented tube.

In order to keep the tube from collapsing, every other indent punch is left out. After the first stroke the end stop 130 and locator element 78 will be shifted to the right an amount equal to the required spacing between adjacent indentations. A second stroke of the press will complete the indentation of the pull rod.

Details of the forming elements 102 are best seen in Figures 7 and 8, it being observed that these elements have laterally extending flanges 156 adapted to seat in a locating groove at one side of the recess 116 as best illustrated in Figure 3. The lower portion of each locating element includes an inclined bottom surface portion 158 which may extend upwardly at an acute angle, and in a practical embodiment of the present invention this angle is approximately 30 degrees. Vertical sections through the lower surface 158 of the forming elements are cylindrical and of constant radius, the radius of curvature being appreciably greater than the radius of curvature of the latching balls for which the forming elements produce cooperating indentations. The lower end portion 160 of the forming elements may be generally spherically formed to the right of the lowest point thereof as seen in Figure 7, this spherical surface having a radius of curvature approximately equal to that of the balls for which the construction is designed.

Referring now to Figure 9 there is illustrated more or less diagrammatically a modified form of apparatus for carrying out the method disclosed herein. In this case a die plate 170 is provided with a support block 172 adapted to support the tubular member 10 thereon. Vertically movable above the die plate 170 is a head plate 174 having a block 176 carried thereby provided with a multiplicity of forming elements 178 which may have end portions identical with those of the forming elements 102 previously described. The block 176 is arranged to carry the forming elements 178 in staggered alignment as illustrated in the figure. The support block 172 is arranged to carry the tubular member 10 with its axis disposed at an oblique angle to the horizontal, and in the illustrated embodiment of the invention the tube is supported at an angle of 45 degrees. Accordingly, the relative movement between the forming elements 178 during the forming action thereof with respect to the tubular member 10 is along a path having substantial radial and axial components with respect to the direction of the axis of the tubular member, and as illustrated the radial and axial components are equal. By obvious design change, the path of advance of the forming elements may be at an angle of 30 degrees to the tube axis, thus giving the same action as the apparatus of Figures 1-3.

While the two embodiments of the mechanism previously described disclose relative movement between the tubular member and the forming elements along paths making angles of approximately 30 and 45 degrees re-

spectively with respect to the axis of the tubular member, this path may be varied somewhat. Also, as suggested by the dotted line position of a single forming element designated 180 in Figure 9, the forming elements might be inclined from the vertical in the apparatus disclosed in Figure 9 so long as the inclination thereof does not exceed the slope of the bottom surface portion 158, or in other words, 30 degrees in the particular form illustrated. In like manner, instead of moving vertically downward as illustrated in Figure 9, the forming elements could move downwardly and to the left at any appropriate angle.

At the deeper end of the indentation, the rounded end of the forming portion acts more nearly perpendicular to the portion of the tube wall which it is forming. The axial component of movement forces metal axially ahead of the forming elements and results in fully formed ball engaging surfaces at the deeper ends of the indentations. So long as the operation is carried out in this way it is found that $\frac{1}{2}$ inch tubular stock having a wall thickness of approximately $\frac{3}{32}$ inches may be indented to a depth of approximately $\frac{3}{32}$ inches so as to produce a satisfactory indented tubular pull rod for automobile brakes.

The drawings and the foregoing specification constitute a description of the improved method and apparatus for indenting tubes in such full, clear, concise and exact terms as to enable any person skilled in the art to practice the invention, the scope of which is indicated by the appended claims.

What we claim as our invention is:

1. The method of providing a tubular brake pull rod with a series of axially aligned indentations at one side only thereof which comprises supporting a length of tubular stock along the bottom and opposite sides, and moving an aligned series of forming elements into forming engagement with the stock along a path occupying a plane radial of the stock and in a direction oblique to the axis of the stock and having substantial radial and axial components with respect to the axis of the stock, thereby forming indentations in the stock which are elongated axially of the stock and relatively deeper at the end thereof toward which the forming elements move.

2. The method of providing a tubular brake pull rod with a series of axially aligned indentations at one side only thereof which comprises supporting a length of tubular stock along the bottom and opposite sides, and moving an aligned series of forming elements into forming engagement with the stock along a path having uniform and substantial radial and axial components relative to the axis of the stock, thereby forming in the stock indentations which are elongated axially of the stock and relatively deeper at the end thereof toward which the axial component of motion causes the forming elements to advance.

3. The method as defined in claim 2 in which the path of advance is at an angle to the axis of the tube equal to about 30-45 degrees.

4. The method of making an indented tubular brake pull rod which comprises supporting a length of tubular stock along the bottom and opposite sides, locating the tubular stock in rotation by inserting a locating key in a slot in one end of the stock, and moving an aligned series of forming elements into forming engagement with the stock along a path occupying a plane radial of the stock and in a direction oblique to the axis of the stock, thereby forming indentations in the stock which are elongated axially of the stock and relatively deeper at the end thereof toward which the forming elements move.

5. The method of indenting tubes which comprises providing a forming element having an elongated forming surface adjacent a tube, the forming surface having a rounded end portion and a portion inclined outwardly from the tube extending from the rounded end portion to the other end of the elongated forming surface, and relatively feeding the forming element into the tube along

a path having both radial and axial components relative to the axis of the tube, the axial component being in such a direction that the rounded end portion of the forming surface moves radially into the tube material and axially thereof in advance of the remaining inclined portion thereof, and enlarging the indentation in the tube laterally and axially from the point of initial contact of the rounded end portion of the elongated forming surface of the forming element in a direction opposite to the axial component of the path of relative movement between the tube and forming element.

6. The method of indenting tubes which comprises providing a forming element adjacent the side of a tube, the forming element having a forming portion elongated axially of the tube, the forming surface having a rounded end portion, the remainder of said forming surface being inclined outwardly from the tube, effecting relative approach between the tube and element to initiate indentation of the tube with the rounded end portion of the forming surface of the forming element, forcing said ele-

10

15
20

ment to move relatively into the tube along a path occupying a plane radial of the tube and making an acute angle to its axis, and extending the indentation in the tube both laterally and axially of the tube in both directions by maintaining the angle between the path of relative advance of the tube and element and the axis of the tube larger than the angle of inclination between the inclined surface of the forming element and the axis of the tube.
